UNITED STATES PATENT OFFICE.

DAVID C. MADER, OF ST. LOUIS, MISSOURI.

GAME APPARATUS.

Application filed January 26, 1925, Serial No. 4,759. Renewed January 18, 1927.

This invention relates to a game apparatus.

An object of the invention is to provide a novel game apparatus for amusement purposes involving some of the principles of familiar games such as bowling, billiards, etc., and in the scoring utilizing some of the principles of certain games in which playing cards are used, and the entire system being designed and arranged so that the principles thereof and the manner of playing the game may be readily understood and in which the scoring is quite simple. The skill with which the manually operated pieces of the apparatus are manipulated is an important factor in the success obtained by the individual players.

Another object of the invention is to provide a game apparatus utilizing a table and balls adapted to be rolled along the table to positions in which they will complete broken electric circuits to light lamps indicating the result of each play.

Another object of the invention is to provide a game apparatus of the type mentioned containing a signal device for indicating the clearing of the table after the completion of each game.

Other objects will appear from the following description, reference being made to the drawing in which—

Fig. 1 is a plan view of my improved game apparatus.

Fig. 2 is a side elevation thereof.

Fig. 3 is an end elevation.

Fig. 4 is a longitudinal vertical sectional view on the line 4—4 of Fig. 1.

Fig. 5 is an enlarged cross sectional view on the line 5—5 of Fig. 1.

Fig. 6 is a diagrammatic view showing the electric circuit system comprised within the invention.

Fig. 7 is an enlarged sectional view showing the device by which the balls are returned to the players after the completion of a play.

Fig. 8 is an enlarged sectional view showing the means by which the broken electric circuits are closed by the balls when successive plays are made.

Fig. 9 is an enlarged sectional view showing the elastic cushion used at the sides and one end of the table.

Fig. 10 is a view showing a signal device for indicating a clearing of the table after the player has completed his plays.

The table is of the approximate form of a

familiar billiard table including the table top 1, upwardly and outwardly inclined side and end walls 2, a wall 3 supporting the top 1 in spaced relation thereto by supporting strips 4. The legs 5 support the entire table. The top 1 terminates a distance inwardly from the forward end of the table, leaving a trough 6 to contain the balls until they are used in playing.

The side and end walls of the table rise to a proper height above the plane of the table top 1 and are connected with the upright confining border walls 7 by frame members 8. The upper surface of the table top 1 and the inner surfaces of the sides 7 are covered with a layer 9 of felt or the like and strips 10 of rubber are secured to the inner surfaces of the side walls to protect them from the impact of the balls and to afford proper resiliency to accelerate the balls in play. A similar strip 11 of rubber extends across the curved rear end 12 of the table.

Near the rear end of the table a series of cavities 13 are formed and lined with metal rings 14 to provide perfectly smooth surfaces and to protect the edges of the holes in the felt located at the cavities. Balls 15 are used in playing the game, the object being to roll the balls along the table in a manner to cause the balls to enter and remain seated in the cavities 13 having the highest scoring value. The cavities may be arranged in the form shown in Fig. 1 in transverse rows which may be curved or not as desired, with the row of highest scoring value adjacent to the rear end of the table and the rows being of progressively decreasing scoring value toward the forward end of the table from which the plays are made; or, the value of the scoring cavities may be arranged or placed in any other position from time to time, as desired.

The result of each successful play is indicated by a signal 16. The signals 16 correspond to the cavities 13, said signals comprising electric lamps each in circuit on one side with a contact member 17 and on the other side with a contact member 18. The contact members 17 and 18 are located in the cavities 13. The contact member 18 is resilient and when free from the weight of a ball is out of contact with the corresponding contact member 17, thereby providing a broken or open circuit, the lamp of which does not become illuminated until a ball rolls into the cavity corresponding thereto. When a ball rolls into a cavity 13 it presses the resilient con-

tact member 18 against the contact member 17, thereby closing the circuit to the corresponding signal lamp 16 which indicates to the players the successful completion of a play and the scoring value thereof.

The balls may be returned to the forward or player's end of the table by drawing a transverse element 19 along the top of the table to engage and actuate the balls toward

10 the players. The ends of the element 19 are supported upon carriages 20, one of which is engaged by a connection 21 from a handle 22 (Figs. 1, 2 and 10), and the other of which is engaged by a similar connection 23 from said handle passing around sheaves 24. As the device 19 moves toward the player's end of the table the carriages 20 contact with the ends of bumper springs 25, but further movement of the device 19 is retarded but not 20 stopped, causing the balls to continue to move toward the player's end of the table until they roll into the trough 6. The device 19 is returned to the rear end of the table by a connection 26 arranged to wind upon a 25 spring actuated roller 27 of familiar construction which acts automatically to wind the connection 26 thereon when the handle 22 is released to return the carriage 19 to its starting position.

30 As an incident to the clearing of the balls from the table by operation of the device 19 a signal is given. In the present instance the signal is an audible one, comprising a bell 28 and a hammer 29 having knuckle joint pivot connection with a lever 30. A projection 31 on the adjacent carriage 20 engages one end of the lever 30 and moves the same in opposition to a spring 32 of the expansion type, which tends to actuate the lever 30 to stroke the hammer 29 against the bell. After the projection 31 passes beyond the lever 30 the spring 32 expands, thereby striking the hammer against the bell and signalling the fact that the table has been cleared.

45 The end of the table containing the cavities 13 is permanently illuminated by lamps 33 having a reflector 34 for deflecting the light to the top of the table.

50 The upper end of the apparatus may be constantly illuminated by lamps 34 behind a glass panel 35 upon which may be displayed the name of the game which I have designated as "Pokerole".

55 From the foregoing it will be seen that I have provided a game apparatus and a method of playing the same, all of which may be readily comprehended and in the playing of which the game goes to the most skillful player. The game may be played and enjoyed by children as well as by older people and, if only reasonable care is exercised, no damage to the apparatus will be caused by playing the game.

65 It is obvious that numerous variations in the construction and arrangement of the

parts of the apparatus may be made without departure from the nature and principle of the invention. I do not restrict myself to the specific form of the invention shown, but contemplate such variations as may be found 70 desirable within the scope of the appended claims.

What I claim and desire to secure by Letters Patent is:—

1. A game apparatus comprising a table, 75 devices supported by the table for indicating the results of successful plays, positions defined upon the top of the table as positions of successful plays, balls arranged to be rolled along the top of the table to said 80 positions in making successful plays, means for operating a corresponding one of said devices when a ball enters one of said positions thereby indicating the making of a successful play, and means indicating when 85 said balls are removed from said positions.

2. A game apparatus comprising a table, devices supported by the table for indicating the results of successful plays, positions defined upon the top of the table as positions 90 of successful plays, balls arranged to be rolled along the top of the table to said positions in making successful plays, means for operating a corresponding one of said devices when a ball enters one of said positions thereby indicating the making of a successful play, and a device for moving the balls from said positions along the table top 95 toward the players.

3. A game apparatus comprising a table, 100 a ball to be rolled along the top of the table, defined successful play positions in the top of the table to receive the ball when a successful play is made, indicating devices corresponding to said positions respectively and each being operated automatically and as an incident to the entry of the ball in the corresponding one of said positions, and means indicating when said ball is removed from any one of said positions.

4. A game apparatus comprising a table, 105 a ball to be rolled along the top of the table, defined successful play positions in the top of the table to receive the ball when a successful play is made, indicating devices corresponding to said positions respectively, an electric circuit from each of said devices to the corresponding one of said positions, a circuit make and break device adjacent to each of said positions controlled by said ball 110 to close the circuit to the corresponding one of said devices automatically and as an incident to the entry of the ball into one of said positions, and means for moving the ball from any one of said positions and along the top of the table towards the player.

5. A game apparatus comprising a table, 115 a ball to be rolled along the top of the table, defined successful play positions in the top 120 of the table to receive the ball when a suc-

cessful play is made, indicating devices corresponding to said positions respectively, an electric circuit from each of said devices to the corresponding one of said positions, a 5 circuit make and break device adjacent to each of said positions controlled by said ball to close the circuit to the corresponding one of said devices automatically and as an incident to the entry of the ball into any one of 10 said positions, a device for moving the balls from said positions toward the players, and a signal indicating when the ball is removed from any one of said positions.

6. A game apparatus comprising a table 15 having a series of cavities in the top thereof, a series of indicating devices corresponding to the cavities respectively, normally open electric circuits leading from said cavities to the corresponding indicating devices, balls 20 arranged to roll along the top of the table and into said cavities, means controlled by the balls entering the cavities to operate

the corresponding indicating devices to indicate the results of plays, and means for moving the balls along the top of the table 25 toward the players after the completion of plays.

7. A game apparatus comprising a table having a series of cavities in the top thereof, 30 a series of indicating devices corresponding to the cavities respectively, normally open electric circuits leading from said cavities to the corresponding indicating devices, balls arranged to roll along the top of the table and into said cavities, means controlled by 35 the balls entering the cavities to operate the corresponding indicating devices to indicate the results of plays, means for moving the balls toward the players after the completion of plays, and means for signalling the 40 fact that the plays have been completed and the balls moved toward the players.

DAVID C. MADER.
